ASH TRAY

Harold G. Arnold, Wooster, Ohio

Application July 8, 1950, Serial No. 11,022

Term of patent 7 years

(Cl. D85—2)

To all whom it may concern:

Be it known that I, Harold G. Arnold, a citizen of the United States, residing at Wooster, State of Ohio, have invented a new, original, and ornamental Design for an Ash Tray, of which the following is a specification, reference being had to the accompanying drawing, forming a part hereof.

The single figure of the drawing is a perspective view of an ash tray, showing my new design.

The opposite side of the article is the same in design as the side shown and the rear surface of the article is of conventional design based on the portions of the novel article disclosed.

I claim:

The ornamental design for an ash tray, as shown and described.

HAROLD G. ARNOLD.
